UNITED STATES PATENT OFFICE.

WILLIAM F. KIESEL, JR., OF ALTOONA, PENNSYLVANIA.

SAFETY-VALVE.

1,262,355.

Specification of Letters Patent. Patented Apr. 9, 1918.

Application filed January 12, 1918. Serial No. 211,574.

To all whom it may concern:

Be it known that I, WILLIAM F. KIESEL, Jr., a citizen of the United States, and residing at Altoona, Blair county, State of Pennsylvania, have invented certain new and useful Improvements in Safety-Valves, of which the following is a specification.

This invention relates to safety valves for steam boilers, particularly to that type of safety valve in which a pilot valve and balancing piston are employed to avoid the use of springs or weights which are not suitable for use in connection with the modern high pressure boilers, such as locomotive boilers. It is the object of this invention to provide such a valve in which the closing is accomplished gradually without a sudden jar or jolt, and in which the amount of blow down pressure may be accurately regulated by means of an adjustment.

The invention will be fully disclosed in the following description taken in connection with the accompanying drawings in which:

25 Figure 1 is a sectional view along the line 1—1 of Fig. 2;

Fig. 2 is a vertical section through the axis of the valve, the valve being closed;

30 Fig. 3 is a view similar to Fig. 2 but showing the valve open.

The casing 10 supporting the movable and other parts of the safety valve is annular in shape and is internally threaded at its lower end for connection to the locomotive or other boiler. On the interior of the casing and above the screw threads is an annular flange 11, formed with the central opening 12 through which the excess steam from the boiler escapes when the valve is open. A short cylinder 13 is located above the flange 11 with its axis coincident with the axis of the casing and is connected to the wall of the casing by webs 14, the spaces between the wall of the casing 10 and the cylinder 13 serving as steam passages through which the escaping steam is conducted into the muffler 15, screw threaded to the top of casing 10.

Rigid with the cylindrical portion 13 and preferably threaded thereto, is an annular member 16 with a central cylindrical opening 17, the axis of the opening being coincident with the axis of the casing. This member constitutes a head for the cylinder 13 and slidably supports with a steam fit, the stem 18' of the main valve 18.

This main valve 18 comprises a cylindrical

member having an outwardly flaring annular flange 19 at its lower end which is provided with an inclined upwardly facing annular seating surface 20 adapted to seat 60 upon a correspondingly inclined and downwardly facing valve seat 21 on the flange 11 and having rigidly secured thereto a piston 22, slidably fitted to the inner surface 24 of the cylinder 13. The piston 22 is adapted to 65 be moved vertically in the cylinder by the steam admitted thereto to operate the main valve, thereby separating the mutually engaging surfaces 20 and 21 to allow the escape of steam from the boiler.

The main valve is hollow and is formed, as shown with a valve seat 25, the stem 18" above this valve seat 25 having pairs of opposed openings or ports 26 and 27 which serve respectively, as ports through which 75 steam may be admitted to and exhausted from the cylinder 13 above the piston 22.

A pilot valve 28 arranged within the main valve 18 is adapted to cooperate with the seat 25. This pilot valve has an upwardly extending stem 29 having a squared end for a wrench, and a threaded portion near the said end. An adjustable sleeve 30 is threaded upon the shank 29 and extends downwardly, its lower end 31 being arranged to 85 control the ports 27. This portion 31 is in reality a sleeve valve controlling the escape of steam through ports 27 from the balancing cylinder, the area of the escape ports at any given instant depending upon the position of the sleeve, and thus upon the position of the pilot valve carrying the same.

The pilot valve is normally held to its seat by means of a coil spring 32, the lower end of which bears against a shoulder 33 integral with the sleeve 30 and whose upper end rests against a threaded nut 34, adjustably secured to the upper end of the main valve by the adjusting nut 35. The position of nut 35 thus controls the degree of compression of the spring 32 and determines the boiler pressure at which the pilot valve opens. The adjusting nut 35 has a series of radial ports 36 therein to permit the escape of steam entering the annular space between the sleeve and the main valve through the port 27, and has an external shoulder or flange 37 serving as an abutment against which the comparatively light coil spring 38 bears. This spring 38 rests at its lower 100 end upon the member 16 and normally tends to keep the main valve seated, so that

it will not fall or open due to its own weight, when there is no steam in the boiler.

The lower end 39 of the adjusting nut 35 is directly above the upper end of the member 16 and these two ends come together 5 when the main valve is opened thereby limiting its downward movement.

With the parts in the position shown in Fig. 2, when the steam pressure in the boiler 10 reaches a predetermined amount the pilot valve is opened against the resistance of spring 32 thus admitting steam into the cylinder above the piston 22 and at the same 15 time the adjustable sleeve 30, which moves with the pilot valve, has been raised such a distance that the outlet port 27 for the cylinder is closed or partially closed, depending upon its adjustment. Steam is then trapped in the cylinder and since the 20 piston 22 has an area greater than the area of that portion of the main valve which is directly exposed to the boiler pressure, the entire main valve moves downward, separating the seating surfaces 20 and 21 and 25 allowing steam to escape therebetween through ports 14 into the muffler and thence into the outside air.

When the boiler pressure has been reduced to a point where the spring 32 is 30 capable of forcing down the pilot valve to its seat and cutting off the inflow of steam into the cylinder it is obvious that the port 27 has been opened by this downward movement and the steam above the piston is thus 35 free to escape upwardly between the sleeve 30 and the wall of the main valve, and to pass out through the openings 36. Steam pressure above the piston is thus gradually reduced and as the boiler pressure is acting 40 on the lower end of the main valve, it is obvious that the latter will seat itself.

This seating of the main valve, however, is not a sudden jolt or jar due to unbalanced upward steam pressure, but is brought 45 about very gradually and takes effect simultaneously with or slightly in advance of the seating of the pilot valve 28. This is accomplished by the operation of the adjustable sleeve 30 in controlling the escape of steam 50 from the piston. As the pressure in the boiler gradually decreases the spring 32 gradually closes the pilot valve and the port 27 is gradually opened thus decreasing the pressure of steam above the piston and gradually seating the main valve. 55

As however, the lower annular end 40 of sleeve 30 is exposed to the upward pressure of the steam when the pilot valve is open, but is not so exposed when the valve is closed 60 it follows that the pilot valve will not close at the same pressure at which it opened, but at a lower pressure. This difference in pressure is known as the blow-down pressure and the amount of such blow-down pressure 65 may be regulated by adjusting the position of

the sleeve 30, not to vary the area exposed, but to regulate the pressure in the balancing cylinder for various positions of the pilot valve, and thus indirectly regulating the blow-down pressure.

By trial adjustments of the sleeve 30, its most effective position may be determined, that is, the position which it will occupy relatively to the pilot valve, to control the escape of steam from the cylinder when the 75 operation of the valve is such that it closes without a jar and when the proper reduction of boiler pressure has been made. When this position has been determined, the adjustment is such that upon the gradual closing of 80 the pilot valve due to the upward pressure of the steam thereon gradually becoming less than the pressure of the spring 32 opposing it, the pressure acting upon the piston to hold the main valve down gradually 85 decreases because of the fact that the orifice through which the steam is passing into the cylinder is becoming more restricted, while the ports through which it may escape are gradually becoming larger, thereby causing 90 the main valve to seat, the pilot valve however closing so slowly that the main valve is seated simultaneously with, or, slightly before the pilot valve.

The device is in no wise complicated or 95 difficult to construct and provides a novel and convenient means for regulating the blow-down pressure of a boiler. The various parts of the mechanism, particularly the seating surfaces 20 and 21 of the main valve 10 are not subjected to great wear as there is no chattering or sudden closing of the valve.

Having thus described my invention what is claimed as new and desired to be secured by Letters Patent is:

1. In a safety valve for steam boilers, a main valve normally held seated by the pressure of steam in the boiler, a cylinder, a piston in said cylinder and connected with said main valve, said piston having an area greater than the area of said main valve, means for admitting steam into the cylinder above said piston when the boiler pressure has reached a predetermined amount, to move the same, thereby opening the main 11 valve, and means for gradually releasing the steam above said piston as the boiler pressure decreases thereby allowing said main valve to gradually close and to seat itself without jarring, said means comprising a valve which automatically opens as the boiler pressure decreases.

2. In a safety valve for steam boilers, a main valve normally held seated by the pressure of steam in the boiler, a cylinder, a piston in said cylinder and connected with said main valve, said piston having an area greater than the area of said main valve, means for admitting steam into the cylinder above said piston when the boiler pressure 11

- has reached a predetermined amount, to move the same, thereby opening the main valve, and a valve controlling the escape of steam from the cylinder above said piston, 5 the opening in said valve becoming greater as the steam pressure in the boiler becomes less, thereby decreasing the pressure upon said piston and allowing the main valve to gradually seat itself without jarring.
- 10 3. In a safety valve for steam boilers, a main valve normally held seated by the pressure of steam in the boiler, a cylinder, a piston in said cylinder and connected with said main valve, said piston having an area greater than the area of said main valve, 15 a pilot valve for admitting steam into the cylinder above the piston when the boiler pressure has reached a predetermined amount, to move the same, thereby opening the main valve, and means connected with and automatically operated by said pilot valve for gradually releasing the steam above said piston as the boiler pressure decreases, thereby allowing said main valve to 20 gradually close and to seat itself without jarring.
4. In a safety valve for steam boilers, a main valve normally held seated by the pressure of steam in the boiler, a cylinder having a port therein, a piston in said cylinder and connected with said main valve, said piston having an area greater than the area of the main valve, a pilot valve for admitting steam into the cylinder above the piston when the boiler pressure has reached a predetermined amount, to move the same, thereby opening the main valve and a valve connected to said means and operated therewith for controlling the port in said cylinder, whereby the ingress and escape of steam into and out of said cylinder are simultaneously regulated, said valve being gradually opened as the pilot valve closes whereby the pressure of the steam acting on the piston is gradually decreased as the boiler pressure decreases and the main valve is allowed to gradually seat itself without jarring.
5. In a safety valve for steam boilers, a main valve having a port therein, a cylinder having a port therein, a piston in said cylinder and connected to said main valve, said piston having an area greater than the area of said main valve, a pilot valve controlling the passage of steam through the port in said main valve and admitting steam into
- said cylinder when the boiler pressure has reached a predetermined amount whereby the main valve is opened, and a sleeve adjustably secured to said pilot valve and controlling the escape of steam through the port in said cylinder, the pilot valve and sleeve operating together to simultaneously control the inlet and escape of steam into and out of said cylinder whereby the movement of the piston and main valve is regulated.
6. In a safety valve for steam boilers, an annular main valve having a port therein, a cylinder axially aligned with said main valve and having ports therein, a piston in said cylinder and rigidly connected to said main valve said piston having an area greater than the area of said main valve, a pilot valve controlling the passage of steam through the port in said main valve to operate the piston and main valve and adapted to open at a predetermined pressure and to close at a lower pressure, and a sleeve adjustably secured to said pilot valve and controlling the escape of steam through the ports in said cylinder, the pilot valve and sleeve operating together to control the steam pressure in said cylinder by regulating its ingress and exhaust, the outlet port being decreased in area and the inlet port opened by a simultaneous movement of said valve and sleeve in one direction, and the outlet port being increased in area and the inlet port decreased in area by a movement of said valve and sleeve in the opposite direction, the main valve being opened upon the first mentioned movement taking place and being gradually closed upon the movement in the opposite direction.
7. In a safety valve for steam boilers, a main valve normally held seated by the pressure of steam in the boiler, a cylinder, a piston in said cylinder and connected with said main valve, said piston having an area greater than the area of said main valve, means for admitting steam into the cylinder above said piston when the boiler pressure has reached a predetermined amount, to move the same, thereby opening the main valve, and means for gradually releasing the steam above said piston as the boiler pressure decreases thereby allowing said main valve to gradually close and to seat itself without jarring.

In testimony whereof I affix my signature.

WILLIAM F. KIESEL, JR.
